DESIGN FOR A RECORDING INSTRUMENT

Frederic J. Suhr, New York, N. Y., assignor to
Consolidated Ashcroft Hancock Company, Inc.,
Bridgeport, Conn., a corporation of Delaware

Application September 5, 1934, Serial No. 53,200

Term of patent 3½ years

To all whom it may concern:

Be it known that I, FREDERIC J. SUHR, a citizen of the United States, residing at New York, in the county of New York and State of New York, have invented a new, original, and ornamental Design for Recording Instruments, of which the following is a specification, reference being had to the accompanying drawing, forming part thereof.

Figure 1 is a front elevational view of a recording instrument showing my new design.

Figure 2 is a side elevational view thereof; and
Figure 3 is a top plan view thereof.

I claim:

The ornamental design for a recording instrument as shown.

FREDERIC J. SUHR.
